UNITED STATES PATENT OFFICE.

JOHN LEICK, OF VERONA, NEW JERSEY.

DESIGN FOR A HAIR-PIN.

SPECIFICATION forming part of Design No. 32,146, dated January 30, 1906.

Application filed December 8, 1899. Serial No. 739,722. Term of patent 14 years.

To all whom it may concern:

Be it known that I, JOHN LEICK, a citizen of the United States, residing at Verona, in the county of Essex and State of New Jersey, have invented and produced a new and original Design for a Hair-Pin, of which the following is a specification.

This invention relates to a new and original design for a hair-pin, and the essential feature resides in the provision of legs or prongs having concaved indentations reversely arranged in a vertical direction and an adjacent body having crossed portions between the said indentations and the head of the pin.

In the drawings, Figure 1 is a perspective view of a hair-pin embodying the features of the design. Fig. 2 is a side elevation of the hair-pin.

Similar numerals of reference are employed to indicate corresponding parts in the views.

The numeral 1 designates the head of the pin, which is curved and has the opposite members 2 and 3 extending therefrom in straight lines and divergently to angular bends 4, and from the latter the said members converge in straight lines, as at 5. The member 2 crosses the member 3, and both members are then again diverged, as at 6, and run in straight lines to curved bends 7 to

form the legs or prongs 8. The legs or prongs 8 are substantially parallel, and from the bend 7 of one an extended downward indentation 9 is formed and regularly curved, and from its outer termination the leg or prong continues into a straight member 10 to provide an entrance extremity. From the bend 7 of the other leg or prong the material is bent upwardly, as at 11, in extended curved form and reversely to the indentation 9 and equally with the latter. The indentations 9 and 11 are respectively arranged below and above a horizontal plane in a vertical direction. From the front terminal of the bend 11 the leg or prong is continued into a straight member 12, parallel with the similar member 45 10 of the opposite leg or prong.

Having thus described the invention, what I claim as new is—

The design for a hair-pin, herein shown and described.

In testimony that I claim the foregoing as my own I have hereto affixed my signature in the presence of two witnesses.

JOHN LEICK.
